CLAIM

The ornamental design for air filter element having attached cover member, as shown and described.

DESCRIPTION

FIG. 1 is a perspective view of one embodiment of an air filter element having attached cover member, the filter element being depicted in broken lines and forming no part of the design sought to be patented;

FIG. 2 is a perspective view of the air filter element having attached cover member depicted in FIG. 1, and shown from an opposite perspective view as FIG. 1, the filter element being shown in broken lines and forming no part of the design sought to be patented;

FIG. 3 is a right side elevational view of the air filter element having attached cover member depicted in FIG. 1, the filter element being shown in broken lines and forming no part of the design sought to be patented; the left side elevational view being a mirror image thereof;

FIG. 4 is a top plan view of the air filter element having attached cover member depicted in FIG. 1, the filter element being depicted in broken lines and forming no part of the design sought to be patented;

FIG. 5 is a bottom plan view of the air filter element having attached cover member depicted in FIG. 1, the filter element being depicted in broken lines and forming no part of the design sought to be patented;

FIG. 6 is a front end elevational view of the air filter element having attached cover member depicted in FIG. 1; and, FIG. 7 is a rear end elevational view of the air filter element having attached cover member depicted in FIG. 1, the filter element being depicted in broken lines and forming no part of the design sought to be patented.
